UNITED STATES PATENT OFFICE.

LAWRENCE D. MORTON, OF SANDUSKY, OHIO, ASSIGNOR TO THE HINDE & DAUCH PAPER COMPANY, OF SANDUSKY, OHIO, A CORPORATION OF OHIO.

PACKING-CASE.

No. 905,449.

Specification of Letters Patent.

Patented Dec. 1, 1908.

Application filed June 15, 1907. Serial No. 379,148.

To all whom it may concern:

Be it known that I, LAWRENCE D. MORTON, a citizen of the United States of America, residing at Sandusky, in the county of Erie 5 and State of Ohio, have invented certain new and useful Improvements in Packing-Cases, of which the following is a specification, reference being had therein to the accompanying drawings.

10 The invention relates particularly to a combined packing and shipping case for fragile articles, especially designed in this instance for lamp shades, and it consists in the novel construction of the case and in the 15 peculiar arrangement and combination of its parts.

In the drawings,—Figure 1 is a perspective view of the case; Fig. 2 is a vertical central section therethrough; Fig. 3 is a perspective view of one of the spacing members; 20 Fig. 4 is a perspective view of the end portions of the spacing member, illustrating the manner of engaging the ends; and Fig. 5 is a perspective view of one of the article-supporting members.

The case is formed preferably of pulp board,—such as double-faced corrugated paper,—which is less expensive and more satisfactory than the ordinary wooden box 30 in that it is adapted to yield or give in use, thus producing an elastic retainer for the article.

The construction comprises a casing proper A of elongated form, as shown in Fig. 1, formed of sides a, a bottom b, reinforced by a plurality of layers, as c, and flaps d adapted to be folded over one upon another to close the open end of the casing.

Arranged within the case described longitudinally thereof is a series of transverse article-supporting members B, extending in parallel alinement, as shown in Fig. 2, each apertured centrally, as at C, to form a seat for the article. Each of these members is 45 proportioned to contact with the sides of the casing proper to be held in its proper position therein, and is also preferably formed of pulp board to form a yielding support.

Interposed between the several transverse members described and acting to space the same one from another is a longitudinally-extending series of cylindrical spacing members D, the opening of each cylinder being considerably greater than the adjoining 55 apertures in the transverse members to per-

REISSUED

mit of the spacer having the proper bearing upon the article-supporting members and to be free from the suspended article. Also, for the purpose of strengthening the case, these spacing cylinders are arranged in axial 60 alinement, as shown in Fig. 2, the entire series resting upon the casing bottom.

In construction, the spacing devices are formed each preferably of a single strip of corrugated board such as described bent into 65 circular form, and the ends interlocking as indicated in Fig. 3, the end portions being scored, as at e and f to permit of the locking engagement.

In filling the box or case, one of the cylindrical spacing members is placed upon the case bottom and the transverse apertured member supported thereon. A lamp shade E is then inserted within the opening in the transverse member, and these several steps 75 are repeated until the case is filled.

It will be observed from the construction and the arrangement of the parts that each shade is entirely independent of the others, and is held in a state of suspension out of 80 contact with the casing proper, so that the liability of breakage is reduced to a minimum.

What I claim as my invention is,—

1. A packing case, comprising an inclosing casing, a series of separated transverse members arranged in parallel alinement independent of and extending longitudinally within the casing, each member being apertured to form a retaining seat for the article 90 and the apertures registering, and a corresponding series of open-ended tubular spacing members also independent of the casing arranged intermediate of the apertured members, the cylinder openings respectively 85 exceeding in area the apertures in the transverse members, the end member of the series forming a support for the several transverse members and the articles carried thereby.

2. A packing and shipping case, comprising an inclosing casing, a single series of separated centrally-apertured plate members 100 therein, each independent of and extending transversely of the casing, and the series longitudinally thereof in parallel alinement, 105 and an axially-aligned series of spacing cylinders also independent of the casing arranged each intermediate adjoining plate members, the cylinder openings being respectively of greater area than the plate apertures, the 110

end member of the series forming a support for the several transverse members and the articles carried thereby.

3. A packing case, formed of pulp board 5 consisting of an elongated casing proper, comprising sides, a closed reinforced bottom and flaps closing the casing top, a single series of flat centrally-apertured plates independent of and extending longitudinally 10 within the casing in parallel alinement, and a corresponding series of annular spacing members for the plates also independent of the casing arranged intermediate of the latter and in axial alinement with the plate 15 apertures.

4. A packing case, comprising an inclosing casing, a single series of centrally-apertured plate members therein, each independent of and extending transversely of the casing, and the series longitudinally thereof in parallel alinement, and an alining series of spacing cylinders also independent of the casing formed each of a single strip of material bent into circular form, and the ends 25 detachably connected, the cylinders being arranged each intermediate adjoining plate members, for the purpose described.

5. A packing case formed of pulp board 30 consisting of an elongated casing comprising sides, a closed reinforced bottom and flaps closing the casing top, a series of separated

transverse members arranged in parallel alinement independent of and extending longitudinally within the casing, each member being apertured to form a retaining seat for 35 the article and the apertures registering, and a corresponding series of open-ended tubular spacing members also independent of the casing arranged intermediate of the apertured members, the cylinder openings respectively exceeding in area the apertures in the transverse members.

6. A packing case consisting of an elongated casing proper comprising sides, a closed reinforced bottom and flaps closing 45 the casing top, a single series of centrally apertured plate members within the casing, each being independent and extending transversely of the casing and the series longitudinally thereof in parallel alinement, and 50 an alining series of spacing cylinders also independent of the casing formed each of a single strip of material bent into circular form and the ends detachably connected, the cylinders being arranged each intermediate 55 adjoining plate members.

In testimony whereof I affix my signature in presence of two witnesses.

LAWRENCE D. MORTON.
